UNITED STATES PATENT OFFICE.

JAMES P. HENRY, OF DAYTON, OHIO, ASSIGNOR TO THE NATIONAL CASH REGISTER COMPANY, OF DAYTON, OHIO.

PROCESS FOR THE REPRODUCTION OF WOOD GRAINS.

No Drawing.

Application filed November 2, 1916. Serial No. 129,205.

To all whom it may concern:

Be it known that I, JAMES P. HENRY, a citizen of the United States, residing at Dayton, in the county of Montgomery and State of Ohio, have invented certain new and useful Improvements in Processes for the Reproduction of Wood Grains, of which I declare the following to be a full, clear, and exact description.

10 The object of this invention is to provide an improved process whereby the graining of woods may be reproduced on substances of other nature than the wood, such as sheet steel or the like in the manufacture 15 of metal furniture.

In view of the unsatisfactory results obtained by the now known processes for the reproduction of wood grains and the like it is the purpose of the present invention to 20 improve, not only the process of reproduction, but the products of such process thereby.

The new and improved process comprises the following steps:

25 In reproducing the grains of quartered oak, mahogany or any other woods having grain, which it is desired to imitate, a piece of wood of desired grain is first selected so that the reproduction will be as artistic as 30 possible. Having a board of selected grain the surface of the same is made as nearly smooth as possible by the ordinary planing and sanding operations and is then given a stain. The pores of the wood will accept the 35 greatest amount of the stain and thus become the darkest places in the surface. The tone is gradually blended off to the high lights or hard spots in the surface of the wood.

40 The board thus prepared is then photographed, reproducing the grain in negative by the usual photographic process. From the negative so obtained, a positive is made, preferably on a photographic film or clear 45 glass, which positive is also obtained by the ordinary photographic process.

Having obtained the positive a print is made therefrom on a sensitized photogravure carbon tissue paper such as ordinarily employed in the intaglio process of printing. It has been found desirable to 50 separate the etched areas to be later obtained and the use of screens as practiced in photogravure is resorted to. After exposure in 55 making the print on the carbon tissue, the

latter is again exposed to light through a screen, preferably of transparent thin lines ruled on glass and crossing each other so as to leave opaque squares instead of transparent squares as in an ordinary half tone 60 screen. This form of screen is well known as the Rembrandt screen in the art of rotary photogravure. Any form of screen may be used such as straight line screens, wave line screens, etc., without departing from the 65 spirit of the present process.

The purpose of the use of the screen, as above described, is to break the etched area into small recesses or cells, which vary in depth according to the shade to be reproduced, and are adapted to receive masses or fields of pigment, as hereinafter described. This breaking up of the etched areas eliminates entirely the difficulties encountered in the use of a wiper or doctor blade. When 70 a wiper or doctor blade is used on a hand engraved or etched metal plate bearing a reproduction of a long open grained piece of wood on which the etched or engraved area is not broken up, the doctor or wiper 75 blade tends to draw out of the unbroken depression more than mere surface pigment, especially when the wiper blade is drawn over the plate in the direction of the grain. This results in leaving in said unbroken depression 80 an insufficient amount of pigment to give a faithful reproduction. With the present invention, however, the small cells into which the etched areas are broken up prevent the excessive withdrawal of the pigment by the wiper blade which can then only 85 remove the surface stain and retains the proper amount of stain which is calculated to give a faithful reproduction of the shades and grain to be reproduced. The carbon 90 tissue is then placed face down on a sheet of burnished metal plate, preferably copper. A cylinder may readily be used in place of the sheet of metal without departing from 95 the spirit of the invention. The carbon tissues so prepared is first allowed to soak in a solution of alcohol and water of equal parts to soften the tissue which is then 100 placed face down in contact with the plate to be etched and squeegeed in contact with 105 the plate.

When the tissue is exposed through the positive and screen, certain portions of the sensitized gelatin are hardened to form an insoluble resist for the etching operation. 110

When the tissue has been squeegeed in contact with the copper plate, warm water is employed to loosen the paper backing and to wash away that part of the sensitized 5 gelatin which is soluble leaving the deposit of insoluble gelatin or resist on the face of the plate. Thus the image is produced on the plate in gelatin photogravure relief corresponding to the lights and shades of the 10 positive through which the light acted. Where the positive is densest the resist is thinnest and where the positive was transparent the resist is thickest. When this 15 process of development is completed, the plate, with the resist, is allowed to dry thoroughly.

The edges and other surfaces of the plate which have not received a deposit of resist as above stated, are protected with a coat 20 of asphaltum preparatory to etching. The plate so prepared is then ready for the etching operation. The etching operation which it has been found preferable to employ, is the usual process of etching a copper plate. 25 The usual mordant, ferric chloride, is used for the purpose of etching. It is found desirable to employ three baths of average variation in strengths running from 45° to 40° Baumé, the variation in climatic conditions 30 determining the strengths to be used, practice showing that in warm weather it is often preferable to start at 48° Baumé while in colder weather to drop to 36° Baumé. Any weak points in the etching 35 may be further developed by local etching by any of the well known methods.

After the plate has been satisfactorily etched the action of the mordant is stopped by the application of a potash bath which 40 also serves to soften the gelatin resist so that it can be brushed from the plate.

It will readily be understood that in the carbon process when the plate is put through the etching baths, the mordant penetrates 45 the thinnest parts of the gelatin resist first, and therefore etches the plate most under these parts. Where the resist was thickest corresponding to the high lights of the positive, the mordant has the least effect on the 50 plate and the etching is the slightest. The effect of the etching will be that where the high lights appeared on the positive the cells formed will be comparatively shallow while in those parts where the positive was 55 dense the cells formed will be correspondingly deep. As the etching is controlled from a true photographic negative of the grain to be reproduced, the varying depth of the cells so formed are such as will give a 60 faithful reproduction of the proper shades.

The plate so prepared is ready for the final operation of reproducing the graining of the wood produced thereon. The operation of reproduction is as follows;

65 The plate is coated with a stain of the

same color as the darkest lines or pores desired of the grain to be reproduced. This is accomplished by submerging the plate, or in the case of a cylinder, revolving said cylinder in a bath of stain. However, the stain 70 may be applied in any other manner in the present process without departing from the spirit of the invention. After the plate has received the coat of stain a "wiper" or "doctor" blade is brought against the surface of the plate and drawn across the surface so that all the surface stain will be wiped off, leaving a deposit of the stain in all of the cells made by the etching process. 75

Having wiped the surface of the plate 80 with a "doctor" blade or wiper, a soft roller is rolled over the surface of the plate. The roller picks up the stain in the various depth cells, which variation in depth of the cells, 85 controls the masses of stain, and will govern the variation in color in a reproduction of the grain.

Having thus picked up on the roller the stain from the cells of the plate or cylinder, said roller is rolled over the part or article 90 to be grained, said part having been previously painted or enameled a ground color, such as required for the grain to be reproduced.

When the soft roll which has picked up 95 the stain from the cells of the plate or cylinder passes over the article to be grained the small masses of pigment picked from the cells will be merged. All lines of union between the masses will be obliterated and all 100 traces of the small etched areas or cells of the etched plate will be destroyed. The varying masses of pigment on the roll due to the varying depth of the cells on the etched plate will still prevail to control the varying shades to be reproduced. 105

The stain thus transferred from the roller to the part or article that is to be grained will give a resultant reproduction which is 110 an exact facsimile of the original board photograph.

Of course, it is to be understood that the color of the stains and ground colors depend entirely upon, and is varied according to, the wood or finish to be reproduced. After the stain has been transferred from the roller to the article which is to bear the reproduction it is desirable, in order to give a more natural appearance, to brush over the grained surface with 115 a soft blending brush. This blending operation, however, is not necessary under all conditions and may be dispensed with, without departing from the spirit of the present process. 120

What is claimed is:—

1. The process of reproducing the grain of wood on a solid surface, which consists in producing a photographic negative of the wood to be simulated; producing from 125 130

the negative a grained plate, the recesses produced by the graining varying in depth with the shade to be produced and arranged to simulate the graining of the original material filling the plate with coloring matter; withdrawing the coloring matter from the recesses of the grained plate by means of an elastic roller to which the coloring matter adheres; transferring the coloring matter 5 from the elastic roller to the surface to be grained and merging the masses one into the other so as to obliterate the lines of union.

2. The process of reproducing the grain 15 of wood on a solid surface which consists in staining the piece of wood to be simulated to accentuate the grain thereof; producing a photographic negative of the wood so prepared; producing from the negative a 20 grained plate, the recesses produced by the graining varying in depth with the shade to be produced and arranged to simulate the graining of the original material; filling the plate with coloring matter; withdrawing the coloring matter from the recesses of the grained plate by means of an elastic roller to which the coloring matter 25 adheres; transferring the coloring matter from the elastic roller to the surface to be grained and merging the masses one into the other so as to obliterate the lines of union.

3. The process of reproducing the grain 35 of wood on a solid surface, which consists in producing a photographic negative of the wood to be simulated; producing from the negative a grained plate, the recesses produced by the graining varying in depth with the shade to be produced and arranged to simulate the graining of the 40 original material; filling the plate with coloring matter; withdrawing the coloring matter from the recesses of the grained plate by means of an elastic roller to which the coloring matter adheres; transferring the 45 coloring matter from the elastic roller to the surface to be grained and merging the

masses one into the other so as to obliterate the lines of union; and blending the masses of pigment with each other and with the surrounding shades.

4. The process of reproducing the grain of wood on a solid surface, which consists in staining the piece of wood to be simulated to accentuate the grain thereof; producing a photographic negative of the wood so 50 prepared; producing from the negative a grained plate, the recesses produced by the graining varying in depth with the shade to be reproduced and arranged to simulate the graining of the original material; filling 55 the plate with coloring matter; withdrawing the coloring matter from the recesses of the grained plate by means of an elastic roller to which the coloring matter adheres; transferring the coloring matter from the elastic 60 roller to the surface to be grained and merging the masses one into the other so as to obliterate the lines of union; and blending the masses of pigment with each other and with the surrounding shades.

5. The process of reproducing the grain of wood on a solid surface, which consists in producing a photographic negative of the wood to be simulated; producing from the negative a grained plate, the recesses 75 produced by the graining varying in depth with the shade to be produced and arranged to simulate the graining of the original material; filling the plate with coloring matter; withdrawing the coloring matter from the recesses of the grained plate by means of an elastic roller to which the coloring matter adheres; coating the article to be grained with a color corresponding to the ground color of the wood whose grain is 80 to be simulated; transferring the coloring matter from the elastic roller to the coated surface to be grained and merging the masses one into the other so as to obliterate the 85 lines of union.

In testimony whereof I affix my signature,
JAMES P. HENRY.

- the negative a grained plate, the recesses produced by the graining varying in depth with the shade to be produced and arranged to simulate the graining of the original material filling the plate with coloring matter; withdrawing the coloring matter from the recesses of the grained plate by means of an elastic roller to which the coloring matter adheres; transferring the coloring matter from the elastic roller to the surface to be grained and merging the masses one into the other so as to obliterate the lines of union. 5
2. The process of reproducing the grain of wood on a solid surface which consists in staining the piece of wood to be simulated to accentuate the grain thereof; producing a photographic negative of the wood so prepared; producing from the negative a grained plate, the recesses produced by the graining varying in depth with the shade to be produced and arranged to simulate the graining of the original material; filling the plate with coloring matter; without drawing the coloring matter from the recesses of the grained plate by means of an elastic roller to which the coloring matter adheres; transferring the coloring matter from the elastic roller to the surface to be grained and merging the masses one into the other so as to obliterate the lines of union. 10
3. The process of reproducing the grain of wood on a solid surface, which consists in producing a photographic negative of the wood to be simulated; producing from the negative a grained plate, the recesses produced by the graining varying in depth with the shade to be produced and arranged to simulate the graining of the original material; filling the plate with coloring matter; withdrawing the coloring matter from the recesses of the grained plate by means of an elastic roller to which the coloring matter adheres; coating the article to be grained with a color corresponding to the ground color of the wood whose grain is to be simulated; transferring the coloring matter from the elastic roller to the coated surface to be grained and merging the masses one into the other so as to obliterate the lines of union. 15
4. The process of reproducing the grain of wood on a solid surface, which consists in staining the piece of wood to be simulated to accentuate the grain thereof; producing a photographic negative of the wood so prepared; producing from the negative a grained plate, the recesses produced by the graining varying in depth with the shade to be reproduced and arranged to simulate the graining of the original material; filling the plate with coloring matter; withdrawing the coloring matter from the recesses of the grained plate by means of an elastic roller to which the coloring matter adheres; transferring the coloring matter from the elastic roller to the surface to be grained and merging the masses one into the other so as to obliterate the lines of union; and blending the masses of pigment with each other and with the surrounding shades. 20
5. The process of reproducing the grain of wood on a solid surface, which consists in producing a photographic negative of the wood to be simulated; producing from the negative a grained plate, the recesses produced by the graining varying in depth with the shade to be produced and arranged to simulate the graining of the original material; filling the plate with coloring matter; withdrawing the coloring matter from the recesses of the grained plate by means of an elastic roller to which the coloring matter adheres; coating the article to be grained with a color corresponding to the ground color of the wood whose grain is to be simulated; transferring the coloring matter from the elastic roller to the coated surface to be grained and merging the masses one into the other so as to obliterate the lines of union. 25
- In testimony whereof I affix my signature,
JAMES P. HENRY.
